PACKAGE WRAPPING MACHINE

Oscar Sandberg, Toledo, Ohio, assignor to Lynch Corporation, Anderson, Ind., a corporation of Indiana

Application January 29, 1949, Serial No. 73,489

22 Claims. (Cl. 53—42)

1

This invention relates to a package wrapping machine adapted for wrapping a plurality of so-called "sandwiches" within a wrapper, the sandwiches being crackers or cookies with a filling between them such as cheese, peanut butter or the like.

One object of the invention is to provide a machine which receives stacks of sandwiches (about four or five in a stack) and wraps a wrapper around each stack by folding the ends of the wrappers over the ends of the stack and completely sealing the wrapper circumferentially around the stack, following which a label is applied to one or both ends of the wrapped package, all the necessary operations being performed in a rotary head while the head rotates through three-fourths of a circle and the finally wrapped and labeled package being discharged from the rotary head and from the wrapping machine.

Another important object of my present invention is to provide a wrapping machine so designed that it can operate at relatively great speed, that is wrap a relatively great number of packages in a unit of time, this being accomplished by a minimum of handling of the package in the machine while it is being wrapped and all the wrapping operations being performed while the package is held in one position in the rotary head, the head being intermittently operated so that the package is stopped at a number of stations during the three-fourths circle rotation of the package from the intake station of the rotary head to the out-going station thereof.

A further object is to provide a rotary head provided with pockets which successively receive the stacks of sandwiches and the wrappers therefor, certain folding operations of the wrapper being performed by the reception of the sandwiches into a pocket, the pocket then being moved to successive stations where further wrapping operations are performed, some wrapping operations being performed by mechanism operable upon the package while it is in movement, and heating mechanisms being provided to contact with the wrapper at certain stations to heat seal the wrapper around the sandwiches.

Still a further object is to provide a labeling device for efficiently applying a label to an end of the completely wrapped package while it is at one of the stations of the rotary head and for heat sealing the label thereto, after which the rotary head advances further and at another station the completed and labeled package is pushed out of the pocket of the rotary head into a discharge conveyor of the wrapping machine.

An additional object is to provide a rotary head

2

with pockets to receive stacks of sandwiches, the pockets being openable and closable, and being provided with end flap folders for the package which at a certain station are moved to retracted position to permit other end flap folders to operate at that station, the final end folds being completed by rotation of the head to a position between folding and heating plates which fold the last end folds of the wrapper and heat them for effecting complete sealing of the sandwiches within the wrapper.

Another additional object is to provide a wrapping machine in which a rotary head has a relatively great number of pockets for the reception of sandwiches or other articles to be wrapped and rotates each cycle of operation of the wrapping machine an angular distance equal to that between the pockets, wrapper folding operations being performed at various stations throughout a half revolution of the head and the wrapped article being discharged at the end of another one-fourth revolution thereof after a label has been applied to one end of the package, or to both ends if desired.

25 With these and other objects in view, my invention consists in the construction, arrangement and combination of the various parts of my wrapping machine whereby the objects contemplated are attained, as hereinafter more fully set forth, pointed out in my claims and illustrated in the accompanying drawings, wherein:

Figure 1 is a partial side elevation of a wrapping machine embodying my present invention, showing the majority of the elements thereof but omitting most of a rotary head. This view is taken from the left side of the machine, considering the article intake end as the rear end thereof.

Figure 2 is an enlarged plan view of the left hand end of Figure 1 showing the discharge end of the machine.

Figure 3 is a similar plan view of the right hand end of the machine and is a continuation of Figure 2, the rotary head being cut through at the center and sectioned, and the shaft for supporting it having parts broken away.

Figure 4 is an enlarged side elevation of the left half of Figure 1, this view being on the same scale as Figure 2 and being a side elevation of the parts shown in Figure 2.

Figure 5 is an enlarged side elevation of the right hand half of the machine shown in Figure 1 at the same scale as Figures 2, 3 and 4, and is an overlapping continuation of the right hand end of Figure 4.

Figure 6 is a front elevation of operating mech-

anisms of the machine as viewed from the left side of Figure 4, this figure being on the same scale.

Figure 7 is a plan view similar to Figure 3 but omits the rotary head, this figure showing the fourth end flap folding and heating shoes and the first circumferential flap folder omitted from Figure 3.

Figure 8 is a side elevation of the rotary head removed from the machine, this view being of the right side of the head and the parts being shown in the positions they would assume without any of them being actuated as they would be if the head were mounted in the machine.

Figure 9 is a side elevation of one of the pockets of the rotary head and its mounting means from the reverse or left side of the head.

Figure 10 is a left side elevation of a portion of the machine as shown in Figure 5 and illustrating the rotary head mounted in connection therewith.

Figures 11 and 12 are views similar to a portion of Figure 10 and showing the parts in different positions assumed during operation of the machine.

Figure 13 is a plan view of a first circumferential flap folder shown at the left side of Figure 11, the parts being in the position shown in Figure 12.

Figure 14 is an enlarged detail sectional view on the line 14-14 of Figure 13.

Figure 15 is a horizontal sectional view on the line 15-15 of Figure 8 through the center of the rotary head showing details of construction particularly with respect to first end flap folders carried thereby.

Figure 16 is a sectional view on the line 16-16 of Figure 8 showing a package holder.

Figure 17 is an end elevation of one of the pocket units of the rotary head as viewed on the line 17-17 adjacent the left side of Figure 8.

Figure 18 is an enlarged elevation of a package labeling mechanism, this view being taken on the section line 18-18 adjacent the top center of Figure 1.

Figure 19 is a detail sectional view on the line 19-19 of Figure 18.

Figure 20 is a plan view on a slightly enlarged scale of the labeling mechanism shown in Figure 18, with label roll supporting brackets shown in section as on the line 20-20 of Figure 18.

Figure 21 is an enlarged vertical sectional view on the line 21-21 of Figure 20.

Figure 22 illustrates a full size length of a label strip used in connection with the labeling mechanism.

Figure 23 is an enlarged left side elevation of a vacuum valve and the control mechanism therefor used in connection with the labeling mechanism.

Figure 24 is an enlarged left side elevation of a vacuum pump and adjacent mechanism of the wrapping machine.

Figure 25 is a fragmentary detail showing a trip clutch for the labeling mechanism.

Figure 26 is a fragmentary detail showing the control mechanism for the trip clutch of Figure 25.

Figure 27 is another view of the trip clutch of Figure 25 as taken on the section line 27-27 thereof.

Figure 28 is a plan view of certain portions of Figure 20 to show operating details of the labeling mechanism, the label roll supporting brackets

being shown in section on the line 28-28 of Figure 21.

Figure 29 is an enlarged sectional view on the line 29-29 of Figure 6 showing the cam for operating the trip clutch and other parts of the mechanism.

Figure 30 is an enlarged left side elevation of the outlet conveyor of the wrapping machine with portions broken away and other portions shown in section to illustrate details thereof, together with adjacent parts of the machine in relation thereto.

Figure 31 is a plan view of the outlet conveyor of Figure 30.

Figure 32 is a cross section through a package of four sandwiches wrapped in my machine.

Figure 33 is a similar view of a five sandwich package, the machine being readily adjustable for either size package.

Figure 34 is a diagrammatic view of the drive mechanism between a main shaft and some of the remaining parts of the mechanism of the wrapping machine which parts rotate continuously, and

Figure 35 is a similar diagrammatic view of other parts of the machine which are rotated intermittently.

On the accompanying drawings, I have used the reference numeral 40 to indicate a front frame member and 41 a rear frame member. The frame members 40 and 41 are connected together at their upper ends by a table 42. A pair of rotor supporting side frames 43 of inverted U-shape are mounted on the table 42 and are provided with bearings 430 which rotatably support a rotor shaft 44.

A rotary package carrying and wrapping head indicated generally by the reference character 40 and shown per se in Figure 8 is provided including side plates 45 and 46 secured to the shaft 44 by a key 47. For simplicity in referring to the rotary head R, I will hereinafter call it merely a "rotor." The rotor R is provided with eight sandwich and wrapper receiving pockets arranged radially as shown generally in Figure 8 and is rotated 45 degrees or one-eighth of a revolution each cycle of operation of the machine so that any one pocket during one complete rotation of the rotor assumes eight different positions or stops at eight different stations. These stations have been numbered (1) to (8) in the specification and are shown within circles throughout various figures of the drawings for convenient reference to the different positions or stations and the operations that take place at those stations.

For effecting one-eighth revolution or angular rotation of 45 degrees of the rotor R each cycle of the machine, I provide a sprocket 160 on a shaft 434 around which a chain 161 extends. This chain also extends around a sprocket 162 on the rotor shaft 44 as in Figure 5. An idler sprocket 163 is provided for taking up play in the chain. Throughout the drawings, some of the sprockets and chains are shown merely diagrammatically to avoid the crowding of details.

The sprocket 160 has three-fourths as many teeth as the sprocket 162 so that each sixth of a rotation of the shaft 434 results in one-eighth rotation of the shaft 44 as required for stopping the pockets of the rotor at the eight different stations designated.

One of the pockets of the rotor will now be described. On each rotor side plate 45 and 46

a guide block 48 is provided in which a bar 49 is slidably mounted. Each bar carries a stud 50. A bracket 51 is adjustably secured by a set screw 52 to the left side stud 50 and a companion bracket 53 is secured also by a set screw 52 to the right side stud 50.

A stud 54 is retained in the bracket 51 by a set screw 55 and carries a first end folder plate 56. A companion first end folder plate 57 is pivoted at 57a to the bracket 53 and biased toward the plate 56 by a spring 58. A tube 59 is riveted at 59a to the end folder plate 57 to enclose and protect the spring and thereby insure its proper operation.

The bars 49 are freely slidable by gravity in the guides 48 of the rotor R but positive means for moving them is provided as will hereinafter appear. A portion of this means cooperates with rollers 60 on studs 61 which are secured to and project from the bars 49, the cover plates for the guides 48 being slotted as shown at 62 in Figure 8 to permit the studs to project therethrough.

Each rotor pocket further includes a stationary front plate 63 and a movable back plate 64. The plate 63 is carried by extensions 65 of the side plates 45 and 46 and each back plate 64 is carried by an arm 66 clamped at 66a to a stub shaft 67 which in turn is rigidly mounted in a pair of arms 68 which are pivoted on studs 69 extending from the side plates 45 and 46 (see Figure 16). These arms may be adjusted about the studs 69 and the adjustment then retained by clamp screws 70 passing through arcuate slots 71 of the arms 68 and threaded into the side plates 45 and 46 as most clearly shown in Figure 9.

Each stub shaft 67 (Figure 16) has an arm 72 secured thereto which carries a roller 73 to be engaged by an actuating means which will now be described. Referring to Figure 10, it will be noted that the lower pocket is opened, that is the back plate 64 is swung away from the front plate 63. This is accomplished by a roller 341 carried by a rock arm 342 as shown in Figures 3 and 10. The arm 342 is pivoted on a stud 393 as best shown in Figure 5. The stud is anchored in a boss 394 of one of the side frames 43. The arm 354 is oscillatable on the stud between collars 395 and 396 secured thereto. The roller 73 of the lowermost rotor pocket and its arm 72 are illustrated fragmentarily by dot and dash lines in Figure 10 so as to show the relationship of the parts when the pocket is open.

A link 343 is connected by a ball and socket connection 362 to the arm 342 and terminates in a second ball and socket connection 344 on the lower end of a rock arm 345 (Figures 2 and 4). The rock arm 345 is secured to what I shall term a main rock shaft 346 inasmuch as this rock shaft has a number of actuating elements secured thereto for various mechanisms of the machine.

The main rock shaft 346 (Figure 4) is rocked by means of an arm 347 secured thereto and a link 348 having its upper end pivoted to one end of the arm 347. The link 348 has on its lower end a fork 349 as shown in Figure 29. The fork 349 straddles a shaft 108 and carries a roller 350 that travels in a cam slot 351 of a cam 352. Thus rotation of the shaft 108 is converted into reciprocating movement of the link 348 and oscillatory movement of the arm 347 and the main rock shaft 346.

The upper end of the rock arm 345 has one end of a link 353 pivoted thereto as shown in Figure 75

2 and a similar arm 354 on the other end of the main rock shaft 346 has a similar link 355 pivoted thereto. The links 353 and 355 extend rearwardly to connect as in Figure 3 with rock arms 356 and 357 depending from rock shafts 358 and 359. The rock shafts 358 and 359 are journaled in the side frames 43. The inner ends of the rock shafts 358 and 359 are provided with arms 360 and 361 clamped respectively thereto, adapted at times to engage the rollers 60 of the studs 61 of the lowermost rotor pocket at station (1), the arms 360 and 361 being curved for this purpose as shown in Figure 5 and dotted in Figure 10. These arms insure that the bars 49 at station (1) are in their lowermost position and retained in that position while a stack of sandwiches is being elevated into the rotor R by a ram head 90 as will be later described.

Any pocket at station (7) which is the discharge station must again be opened and this is accomplished by a lug 363, the position of which in relation to the roller 73 is illustrated in section in Figure 8 even though the rotor is removed from the machine in this figure. This lug is also shown in Figures 3 (left side) 5 (left side) and 26 (right side). It is carried by the upper end of a rock shaft 364 that is slideable through a bearing 365 rotatably mounted in one of the side frames 43 to permit slight swinging of the rod as a result of its lower end being pivoted to a rock arm 366 shown mainly by dotted lines in Figure 4 and in Figure 2. The arm is an extension of the arm 347, the rod 364 being thereby reciprocated in synchronism with the rocking of the rock shaft 346. Once each cycle of operation of the machine the lug 363 is moved downwardly from the position shown in Figure 8 for the purpose of swinging the back plate 64 at station (7) upwardly thus permitting the package to be expelled from the rotor R.

The means for expelling the package at station (7) is a package ejector shoe 78, this being effected by rocking an arm 79 that carries it from the dot and dash line position in Figure 8 that it would have assumed by reason of a package being present in the rotor pocket to the solid line position under the rocking action of a rock arm 367 on the rock shaft 346 at the lateral center of the machine. As shown in Figure 2 this rock arm 79 engages a roller 83 of a fork 82 of the arm 78.

The upper end of the rod 364 has a pair of collars 368 thereon between which the forked end of a flat strap-like bar 369 is positioned as shown in Figure 26. The bar 369 is secured to a stub shaft 370 which can be rotatably adjusted in a split bearing 371 of a bell crank 372. After adjustment is effected the stub shaft is locked by a clamp screw 373.

The bell crank 372 is pivoted at 374 on a bracket 375 extending upwardly from a bracket 410 at the front end of the machine and pivotally carries at its opposite end, as indicated at 376, a trip rod 377. One end of the trip rod 377, as indicated at 378, is adapted to extend into a pocket and engage a package P at station (5). The other end thereof has a link 379 pivoted thereto for a purpose which will hereinafter appear.

The back plates 64 are normally biased to the closed pocket position illustrated in Figure 8 by springs 74 connected between screws 75 carried by the arms 72 and pins 76 projecting from the side plate 46 as shown in Figure 16. Also mounted on the pins 76 are stop arms 77 project-

ing toward the arms 72 and limiting their position in response to the springs 74.

The package ejector shoes 78 are pivoted to the arms 79 which arms are normally engaged with the inner edges of the front plates 63 by means of springs 80 as shown in Figure 8. Each arm 79 is then pivoted on a pin 81 carried by the side plates 45 and 46 and its forked extension 82 carries between its arms the roller 83 adapted to be engaged by the arm 367 for wrapped package 10 ejecting purposes as already described.

A pocket conveyor is provided for delivering stacks of sandwiches 84 into the wrapping mechanism (see Figure 1). This conveyor comprises a chain 85 around three sprockets 86, 87 and 88 (see Figure 35 for the sprocket 88) and provided with channel-shaped pockets 89 to receive the stacks of sandwiches placed therein by a suitable feeding mechanism such as shown in my copending application, Serial No. 90,990, filed May 2, 1949. A ram head 90 (Figures 1 and 10) is adapted to pass up through an opening 91 in each pocket 89 as the pocket stops in alignment with the ram. The ram head is carried by a slide 92 which slides on guide rods 93 as shown in my copending application, Serial No. 654,079, filed March 13, 1946, now Patent No. 2,567,405, issued September 11, 1951. The rods 93 are mounted stationary with respect to the table 42.

For vertically reciprocating the slide 92 I provide an arm 94 connected by a link 95 with the slide, the arm 94 being mounted on a rock shaft 46 journaled in the frame members 40 and 41. The rear end of the rock shaft 96 has secured thereto a lever 97 connected by a link 98 to a lever crank 99 on a main drive shaft 100. The shaft 100 may be driven at a suitable speed in any desired manner such as by connection through step-down gearing and a belt with an electric motor as shown in my Patent No. 2,283,097, issued May 12, 1942, wherein the shaft 24 corresponds to the shaft 100 in the present specification.

A bevel gear 101 on the front end of the main drive shaft 100 meshes with a bevel gear 102 on a cross shaft 103 which is journaled in bearings on the front frame member 40. The arrangement is best shown in Figures 1, 24 and 33.

On the cross shaft 103 a sprocket 104 is provided around which a chain 105 extends. An idler sprocket 106 is mounted on a bracket 107 and the shaft 108 is journaled above the idler. The chain 105 extends over the idler sprocket 106 and around a sprocket 109 on the shaft 108, the shafts 103 and 108 rotating clockwise. A Geneva movement is provided including a crank arm 110 on the shaft 108 carrying a roller 111 for periodically engaging notches 112 of a disc 113. The disc has arcuate portions 114 in its periphery adapted to be engaged by a locking disc 115 on the shaft 108 to lock the disc 113 against rotation except when the roller 111 enters one of the slots 112 for imparting one-sixth rotation to the shaft 434 each time the shaft 108 rotates. At that time an arcuate depression 116 in the disc 115 permits the portions of the disc 113 adjacent the outer ends of the slots 112 to swing from one position through an arc of 60° to the next position. Thus intermittent rotation is imparted to the shaft 434.

This intermittent motion is transmitted to the pocket conveyor chain 85 by means of a chain 117 around sprockets 118 and 119 and an idler sprocket 120. The timing is such that the shafts 100, 103, and 108 rotate once each cycle of operation of the wrapping machine and the shaft 434 75

rotates one-sixth revolution during each cycle, causing the chain 85 to advance a distance equal to the spacing, center-to-center, of the pockets 89 of the pocket conveyor. Thus the ram head 90 is elevated once for each pocket of the pocket conveyor during the time that the pocket is stopped in alignment with the ram.

Referring to Figure 10, a wrapper 121 in the form of square or rectangular sheet of cellophane, paper or the like is adapted to be fed from a suitable wrapper feeding and cutting device such as shown in my Patent No. 2,283,096, issued May 12, 1942 onto the top of the table 42 beneath a pair of guide strips 132. The ram head 90 is adapted to elevate a stack of sandwiches against the wrapper and then into the pocket of the rotor at station (1) as shown in Figure 11 which drapes the wrapper inverted U-shape over the sandwiches, following which it is desirable to effect a circumferential flap folder operation on the two depending circumferential flaps 121a and 121b of the wrapper. This is accomplished by circumferential flap folders which will not be described.

Oscillatably mounted on the shaft 44 is an arm 122 extending downwardly from the shaft and having an arcuate first flap folder plate 123 mounted on its lower end. This plate is ribbed on its top surface as shown in Figure 13 and a pair of guide rods 124 are secured to its lower surface and extend forwardly (to the left in Figure 13).

A cross head 125 is slidable on the rods 124 and is guided against binding by means of a sliding strip 126 extending rearwardly therefrom and having its rear end portion slidable between two of the ribs of the plate 123 above a slot 127 of the plate as detailed in Figure 14. The strip 126 is retained with respect to the slot by means of a cross plate 128 secured to the strip by a rivet 129.

A leaf spring 421 is secured to the cross head 125 as by rivets 422 and has a curved portion 423 to engage the stack of sandwiches as in Figure 12 to hold a first circumferential flap 121a of the wrapper in position. The cross head 125 is biased toward the plate 123 by a spring 130, its normal position being that shown in Figure 11 and its retracted position as shown in Figures 12 and 13.

For oscillating the arm 122 I provide a link 141 which extends forwardly to connect with a rock arm 142 as shown in Figure 4. The arm 142 is secured to a rock shaft 143 to which another arm 144 is secured terminating at its lower end in a roller 145 traveling in a cam groove 146 of a cam 147. The cam 147 is secured to the continuously rotating shaft 108.

Referring to Figure 12, flexible fingers 131 are secured to the rear strip 132 and adjacent their free ends a heater shoe 132 is provided in the form of a block having a pair of bores in which electrical heaters 133 are mounted. The shoe 132 is loosely carried on an arm 134 of a rock shaft 135 journaled on top of the table 42. The loose connection is provided in the form of a stud 136 secured to the shoe and extending loosely through a hole of the arm with a spring 137 interposed between the shoe and the arm.

A second circumferential flap engaging plate 138 is pivoted at 139 to the shoe 132 and is biased to the position shown in Figure 12 by a spring 140. The action of this plate is shown in Figure 11 and will be described later on in the specification.

For moving the shoe 132 each cycle of opera-

tion from the position of Figure 12 to the position of Figure 11 and then back again the shaft 135 is rocked by a lever 148 (see Figure 10) carrying a roller 149. The roller is held against a cam 150 by a spring 151. The cam 150 is mounted on a shaft 152 journalled in bearings 153 mounted on the table 42.

The shaft 152 is rotated by a sprocket 154 and a chain 155 as shown in Figure 34. The chain extends around a sprocket 156 on the shaft 108, an idler sprocket 157 below the sprocket 154 and a sprocket 158 mounted loosely on the main rock shaft 346.

Referring to Figures 3 and 5, a pair of second end flap folder plates 164 are provided. These are supported by rods 165 adjustably clamped in arms 166. The arms are provided with bearings 167 rotatable on studs 168. Each stud constitutes a crank pin of a crank 169 carried by a crank shaft 170. Each crank shaft is journalled in a bearing 171 of one of the side frames 43 whereby a crank shaft is provided for each side of the machine inasmuch as there are two of the frames 43.

Each arm 166 is part of a bell crank, the other arm of which is illustrated at 172. This other arm is forked, the slot being shown at 173. The slot 173 straddles the shaft 152 so that counter-clockwise rotation of the shafts 170 in Figure 5 results in an upward wiping motion of the second end flap folder plates 164 with respect to a package held in the head at station (3) and then an upward and outward motion away from the package while it is being moved from station (2) to station (3) whereupon the plates 164 will have returned in an elliptical path somewhat larger than the circular path of the crank pins 168 to wipe upwardly again with respect to the next package arriving at station (3).

For rotating the cranks 169 each crank shaft 170 is provided with a sprocket 174, and a companion sprocket 175 is aligned therewith on the shaft 152. Two chains 176 are then provided for connecting the two sprockets 174 with the two sprockets 175 to rotate the crank shafts in unison and thereby operate the second end flap holder plates 164 in unison, the space between the crank shafts being unobstructed for the operation of third end flap folder plates 177 which will now be described.

The end folder plates 177 are secured to arms 178, the arms being pivoted at 179 to a bracket 180 best shown in Figure 5. The bracket 180 is carried by a pair of rods 182 slidably mounted in a pair of cross brackets 181 having hubs at their centers through which the rods slide and secured at their ends to rearward extensions 436 of the side frames 43.

The bracket 180 is adapted to be reciprocated by a rock arm 183 supported on a rock shaft 184 journalled in the extensions 436. A link 185 connects the rock arm to the bracket 180. The shaft 184 in turn has a rock arm 186 secured thereto and connected by a link 187 to a rock arm 188 pivoted at 189 to the rear frame 41 (Figure 1) and carrying a roller 190. The roller travels in a cam groove 159 of a cam 191 secured to a shaft 192 which is operatively connected by sprockets 193 and 194 and a chain 195 to the main drive shaft 100 to rotate at the same speed as the drive shaft.

Returning to Figures 3 and 5, the arms 178 carry rollers 196 adapted for coaction with a stationary cam bar 197 secured to the cross brackets 181. The cam bar 197 has an enlarged

head 198 to spread the rollers as will hereinafter appear, a spring 199 serving to normally pull the rollers toward each other and against the cam bar and its head.

5 A cross head 200 is secured to the upper ends of the pivots 179 and is thereby mounted on the bracket 180 to reciprocate therewith. First end flap folder return rods 201 are carried thereby and are provided with depending fingers 202 to at times engage the rollers 60 on the studs 61 of the slide bars 49 previously described in connection with Figure 15.

Referring to Figures 7 and 10, curved heater shoes 203 are provided extending from substantially station (3) to station (5). These shoes are supported at their lower ends by forks 204 pivoted thereto and at their upper ends by similar forks 205 pivoted thereto. The forks 204 are carried by pins 206 and the forks 205 are carried by pins 207. The pins 206 are adjustably supported in bearings 208 of brackets 392 mounted on the side frames 43 and the pins 207 are slidably supported in bearings 209 thereof.

Set screws 210 retain the adjustment of the pins 206, whereas the pins 207 are floatingly mounted and spring biased toward each other by a spring 211. The ends of the spring are connected with collars 437 secured to the opposite pins 207. The collars 437 are so adjusted that the upper ends of the shoes are slightly closer together than the lower ends as illustrated in Figure 7. The shoes 203 are provided with electric heaters imbedded therein and in addition to serving as a means to heat the end flaps of the package that serve as fourth end flap folders as will hereinafter appear.

At station (4) a third heater shoe 212 is provided to contact the periphery of the package when at this station and impart additional heat to the circumferential flaps of the package for heat sealing purposes to insure a properly sealed package. The shoe 212 has a face curved to fit the package and is carried by a rock arm 213 secured to a rock shaft 214. The shaft 213 is journalled in the side frames 43 and a second rock arm 215 secured thereto is connected by a link 216 to the lever 148. Accordingly the shoe 212 moves toward and contacts the package at station (4) at the same time that the shoe 132 likewise moves toward and contacts a package at station (2).

Labeling mechanism is adapted to apply a label to one end of the wrapped package at station (6). This mechanism is shown mainly in Figures 18 to 29. It includes a supporting frame 217 mounted on a bar 438 and spacers 435 (see Figure 18) secured to a plate 291 mounted on one of the side frames 43. A strip of labels 218 of suitable shape such as shown in Figure 22 is rolled from a reel 219 supported on a shaft 220 journalled at the top of the frame 217.

The strip of labels passes under a pair of rollers 221 rotating on a rod 222 and then passes under a shaft 223 after which the strip extends upwardly and over a feed roll 224. The feed roll has projections 225 engageable in notches 226 in opposite sides of the strip of labels. A metal strip 306 located between the rollers 221 has an eye encircling the rod 222 and curves up over the feed roll 224 to hold the label strip thereagainst. The labels are adapted to be cut at the dot and dash line 227 in Figure 22 as will hereinafter appear.

For driving the feed roll 224, I provide a four tooth ratchet wheel 228 and a pawl 229 carried

by a rock arm 230. A spring 231 serves to bias the pawl toward the ratchet wheel. The rock arm is rocked by a link 232 extending downwardly and pivoted to a rock arm 233 on a shaft 234. The upper end of the link 232 is connected to the arm 230 by a ball and socket connection 334. In Figure 18 the upper limit of movement of the arm 233 is illustrated by solid lines and its lower limit of movement by dotted lines.

A strap 235 (Figure 18) extends over the shaft 234 and has its ends connected with the clip 236 and its lower end anchored to a clip 237a (Figure 6) to brake the shaft 234 against excessive movement due to momentum. The shaft 234 is driven by a sprocket 238, a chain 239 and a sprocket 240, an idler 241 being provided to take up play in the chain. The sprocket 240 is freely rotatable on the shaft 108, a special clutch being provided for driving the sprocket from the shaft being described later herein.

In order to prevent return rotation of the ratchet wheel 228 with the pawl 229, I provide a brake drum 241 on the shaft 244 on which the feed roll 224 is mounted. A brake band 242 surrounds the drum 241 with a brake lining 243 interposed between the two. The brake band 242 has an arm 245 anchored to a stationary pin 246, all as shown in Figure 18. A bolt 429 provides means to adjust the tension of the brake band 242.

Referring to Figure 22, a companion feed roll 248 is provided for cooperation with the feed roll 224 to keep the label strip 218 against the roll 224. The roll 248 is mounted on a shaft 252 carried by an arm 253 which as shown in Figure 18 is adjustably mounted on a stud 254 carried by the frame 217 and provided with a clamp screw 255 to retain the adjustment. Thus the distance of the surfaces of the rolls 224 and 248 from each other can be made substantially equal to the thickness of the particular label being used in the machine.

For driving the feed roll 248 in synchronism with the feed roll 224, I provide gears 249 and 250 meshing with each other. A knob 251 (see Figure 20) on the shaft 244 is provided for manually rotating the feed rolls (while a set screw 433 of the ratchet wheel 228 is loose) to synchronize the labels 218 in the label strip with relation to cutter knives which will be described in the following paragraph so that they cut at the line 227 of Figure 22 when the pawl 229 is advanced to its clockwise limit.

Figure 21 shows a stationary cutter knife 256 for the label strip and an oscillating cutter knife 257 coacting therewith. The knife 256 is mounted on a pair of stationary brackets 258 clamped to the shaft 223. The knife 257 (a portion broken out to show the label being cut off) is pivoted on a bolt 260 as shown in this figure and in Figure 28, a spring 261 being provided to hold the movable knife 257 frictionally against the stationary knife 256. Label guide plates 263 and 264 are provided adjacent the knives 256 and 257 to guide the label strip properly into position for being cut thereby.

For oscillating the knife 257 I provide a link 265 shown in Figures 18, 20 and 22 which extends to a rock arm 266 on a shaft 267 journaled in a bracket 276 mounted on the side frame 43. A second rock arm 268 on the shaft is connected by a link 269 with an arm 270 (see Figures 18 and 19) pivoted at 271 to a bracket 272 mounted on the bracket 277 which in turn is mounted on the frame member 40. The arm 270 carries a roller

273 engaged against the surface of a cam 274 by a spring 275. The spring 275 is connected at its upper end with a rod 278 extending from the arm 270 and at its lower end to a headed pin 279 extending from a bracket 277. The cam 274 is mounted on the shaft 234 which drives the ratcheting mechanism for the label feed rolls.

Returning to Figure 21, a label carrying head 280 is provided having an electric heater 281 therein. The head 280 is carried by a spring 282 rigidly secured in the head at one end and to a slide 283 at its other end by being mounted on a stud 284 thereof. The slide 283 includes a bottom plate 285 sliding in a guideway 286 mounted on the cross member 438 and has a depending bracket 287 connected by a link 288 with a rock arm 289. The rock arm 289, as shown in Figure 18, is mounted on a rock shaft 290 journaled on the bracket 291. An arm 292 also secured to the rock shaft 290 serves to impart rocking movement thereto through a link 293 extending downwardly to a bell crank having arms 294 and 295 as shown in Figures 1 and 24. The bell crank is pivoted at 296 and carries a roller 297 to travel in a cam slot 298 of a cam 299. This cam is mounted on the cross shaft 108.

To conduct electricity to the heater 281 in the head 280, I provide a pair of carbon brushes 425 slidably mounted in sockets of a brush holder 426 mounted on a supporting plate 428 (see Figure 20). Springs 427 bias the brushes toward a pair of contact strips 424 mounted on the support 283. The wiring from a source of current supply to the contact strips and from the brushes to the heater, being obvious, have not been illustrated.

A label holding rod 300 is provided as shown in Figure 21 and mainly by dotted lines in Figure 20. This rod has an arcuate portion 301 extending from a hub 302 as shown in Figure 18 which hub is oscillatably mounted on a stud 303. An arm 304 extends from the hub and is connected by a link 305 with the slide 283.

The label carrying head 280 is provided with a vacuum passageway 306 as shown in Figure 21 which communicates with a vacuum pipe 307 extending to a flexible hose 308 as shown in Figure 20. A clamp 309 on the hose is connected by a bracket arm 310 with the slide 283 so that the pipe 307 and the clamp reciprocate as a unit therewith.

The hose 308 is of course flexible so as to permit such reciprocation and extends downwardly to an elbow 311 as shown in Figures 1 and 23 mounted in the top of a valve body 312. The valve body 312 is mounted on the frame 40 by means of screws 313 and has a vent 314 open to atmosphere whenever a vent closing plug 315 is removed therefrom.

The plug 315 is carried by a rock arm 316 pivoted at 317 to a bracket 318 extending from the valve body 312. Another elbow 319 communicates with the interior of the valve body 312 and is connected by piping 320 with a filter 322 (Figure 24) on which a vacuum gauge 321 is mounted. The filter 322 is mounted on the intake 323 of a vacuum pump 324 driven by its own motor 325 independent of the motor that drives the main drive shaft 100.

From the construction of the parts just described it is obvious that vacuum in the head 280 is produced whenever the plug 315 of Figure 23 is against the vent at 314, thus holding the label strip against the head by vacuum. When the plug 315 is off the vent however (dotted posi-

tion of lever 316 in Figure 23), the pump 324 merely sucks in atmospheric air entering the vent 314 instead of producing a vacuum in the passageway 306 of Figure 21.

The plug 315 is normally seated against the vent 314 by a spring 326 as shown in Figure 23. To unseat it against the bias of the spring a link 327 is provided extending to a bell crank 328 pivoted at 329 to a bracket 330. The bell crank 328 carries a roller 331 cooperable with a cam 332 on the shaft 152.

Opposing the label carrying head 280 a floating head 333 shown particularly in Figures 18 and 20 is provided. The heads 280 and 333 hold the package while the label is being applied. The position of the package in relation to the floating head 333 is shown in these two figures, the package itself bearing the reference character P. The head 333 is carried by a rod 335 slidable in a sleeve 338 mounted in a stationary bracket 336. The outer end of the rod is provided with an adjustable stop collar 337 and a spring 339 is positioned on the rod 335 between the tube 338 and the head 333.

It is desirable that the labeling device operate only when there is a package to be labeled. Otherwise labels will be cut off and wasted. This is accomplished by a clutch mechanism, the operation of which is under control of the trip rod 377 shown in Figure 26. The clutch mechanism itself is of the single rotation type responsive to the trip rod and is shown in detail in Figures 25 and 27, its position with respect to the other operating mechanism being shown best in Figure 6.

A hub 380 of the sprocket 240 has an arm 381 to which a dog 382 is pivoted. This dog has one end (indicated 383) biased toward a disc 384 so as to be engaged thereby as the disc rotates clockwise in Figure 27, the disc being secured to the shaft 108 to rotate therewith. The bias for the dog is provided by means of a spring 386 having one end secured to the dog and its other end secured to a pin 387 projecting from the hub 380.

A bell crank 388 is pivoted on a stud bolt 389 threaded into the frame 40. The horizontal arm of the bell crank 388 in Figure 25 is connected to the link 379 which extends upwardly to the trip rod 377 in Figure 26. The vertical arm of the bell crank carries a stop pin 390 adapted to engage a shoulder 391 of the dog 382 when the stop pin is in alignment with the plane of rotation of the dog as shown by solid lines in Figure 25. When the stop pin is out of this plane of rotation as shown by dotted lines the dog is free to remain engaged with the shoulder 385 so that rotation of the sprocket 240 with the shaft 108 continues.

Whenever the pin is returned to an obstructing position, a cam surface 397 will engage the pin and this will rock the dog clockwise on its pivot 398 to the arm 381, and the rotation of the sprocket will finally be stopped at a predetermined position by the shoulder 391 of the pawl engaging the stop pin 390.

At station (7) where the packages P are pushed out of the rotor pockets as shown in Figure 30, a discharge conveyor is provided in the form of a platform 399 and a pair of flexible belts 400 and 401 arranged in vertical planes. The belt 400 extends around a pair of rollers 402 and 403, the roller 402 being driven from a conveyor drive shaft 404 by a spiral gear 405 thereon meshing with a spiral gear 406 on the shaft of the roller 402. The belt 401 is driven in the same

manner by means of similar parts 402, 403, 405 and 406 except that the teeth of the spiral gears 405 and 406 are reversed as shown in Figure 31 to produce opposite rotation and subsequently movement in the same direction of the adjacent stretches of the belts 400 and 401 which engage the ends of the package P shown dotted in this figure.

For adjustability to accommodate either four or five sandwich packages as shown in Figures 32 and 33, the rollers 402 and 403 are journaled on brackets 407 slotted at 408 for clamp screws 409 threaded into supporting bars 410.

The conveyor drive shaft 404 is driven by a chain 411 over a sprocket 412 on the shaft, the chain extending around another sprocket 413 (see Figure 34) on a shaft 414. Another sprocket 415 on the same shaft is engaged by the chain 155 after it leaves the idler sprocket 158 which is freely rotatable on the main rock shaft 346.

At the discharge end of the conveyor 399-400-401, I provide a take-away conveyor comprising a flexible belt 416 having its upper stretch travelling on a platform 417 and extending around a suitable roller 418 and a similar roller not shown beyond the left end of Figure 30. Since these conveyors are of ordinary construction I will not go into detail except to say that side plates 419 are provided for the ends of the packages and the roller 418 is driven by a chain 420 around sprockets 421 and 422 of the roller 418 and the conveyor drive shaft 404 respectively. Thus the take-away conveyor is driven from the conveyor drive shaft.

Practical operation

Referring first to Figure 10, the pocket of the rotary head R at station (1) has its back plate 64 opened by roller 341 on the arm 342 of Figure 3 (dot and dash position) engaging the roller 73 of the arm 72 for that particular back plate as shown by the dotted line positions in Figure 10. As the ram head 90 elevates the stack of sandwiches 84 into this pocket, the stack will engage the wrapper 121 (at dotted position shown in Figure 12) and carry it up into the pocket as in Figure 11, the package ejector shoe 78 for that pocket being pushed up by the wrapper and the sandwiches under it to the position shown against the bias of the spring 80.

As the stack of sandwiches is forced into the pocket of the head by the ram, a first end flap fold indicated 1 is performed by reason of the portions of the wrapper 121 beyond the ends of the sandwich stack engaging the first end flap folder plates 56 and 57. Referring to Figure 15 the spring 58 behind the plate 57 provides some resiliency for imparting slight pressure to the first end flaps 1 and for taking care of slight variations in total height of the stack.

The next step in the operation is illustrated in Figure 12 wherein the arm 122 has swung toward the right for causing a rear circumferential flap 121a of the wrapper to be tucked in under the stack. This operation is accomplished by the advancing edge of the arcuate plate 123, and before its motion is completed the curved part 423 of the leaf spring 421 engages the sandwiches as in Figure 12 which stops the motion 65 of the parts 124, 125, 126 and 421 whereupon the arcuate plate 123 continues to move with the spring 130 stretching and thereby permitting such movement while the parts just enumerated remain stationary. This insures that the flap 70 121a is held in position until the rotor R starts

to move the pocket at station (1) toward station (2) as shown by dot and dash lines in Figure 12.

Such movement causes the flap 121b to be dragged by the fingers 131 to a position wrapped around the periphery of the package as shown, following which further movement of the package to station (2) as shown in Figure 11 causes the plate 138 pivoted to the heater shoe 132 to aid in dragging the flap 121b to its final position.

When the final position is reached, that is when the sandwiches are stopped at station (2), the shoe 132 is elevated from the position of Figure 12 to the position of Figure 11 for momentarily applying heat to the circumferential flaps 121a and 121b, thereby heat-sealing them together.

As the heater shoe 132 recedes again to the position shown in Figure 12 the rotary head rotates another eighth revolution to bring the stack of sandwiches to station (3) shown in Figure 10 where the parts shown in Figures 3 and 5 operate thereon to perform the second and third end flap folds.

The second end flap fold 2 is performed by the plates 177 being propelled toward the pocket and engaging the extending ends 2 of the wrapper to bend them over the ends of the stack. As the plates 177 advance, their rollers 196 engage the cam head 198 which spreads the rollers against the bias of the spring 199 and swings the plates 177 toward each other for pressing the second end flaps against the ends of the stack.

In order that the first end flap folder plates 56 and 57 shall be out of the way of the second end flap folder plates 177 the rods 201 moving simultaneously therewith engage the rollers 60 through the fingers 202 carried thereby which slides the bars 49 back toward the center of rotation of the rotor R.

After the plates 177 have performed their function, the third end flap folder plates 164 wipe upwardly for performing the third end flap fold 3. This is done while the plates 177 are still holding the second end flaps 2 in position so that they are not dislodged from their folded positions.

The plates 177 then retract as the rotor starts to move again and the plates 164 move upwardly a slight distance along with the rotor due to the way these plates are mounted on the bell cranks 166-172 and actuated by the cranks 169. The fourth end flaps 4 are then formed by the ends of the package wiping up into the heater shoes 203.

All flaps enclosing the package are now completed and when the package hesitates at station (4) the heat of the shoes 203 seals all four end flaps more securely while at the same time the shoe 212 is moved into engagement with the two circumferential flaps 121a and 121b to further insure completion of the heat-sealing action. Since the shoes 203 converge toward their upper ends under the bias of the spring 211, a firm pressure of the end flaps 1, 2, 3 and 4 under the heat sealing action of the shoes is had.

At station (5) nothing occurs except for the trip rod 377 to check and see if there is a package at this station so as to activate the label clutch of Figures 25 and 27 for applying a label to the package. This checking is accomplished by the cyclic lowering of the bell crank 372 of Figure 26 by the rod 364 which reciprocates vertically each cycle of the machine. As the bell crank 372 is lowered the bell crank 388 of

Figure 25 which is normally held in the clockwise position by a spring 423a will remain in that position if there is no package at station (5), the trip rod 377 being in the dash line position at that time.

When there is a package at station (5) the end 5 378 of the trip rod 377 will engage its top surface and this will result in the left end of the rod 377 in Figure 26 being depressed as shown by dot and 10 dash lines for swinging the bell crank 388 of Figure 25 to the dot and dash position, thus permitting the dog 382 of Figure 27 to drop at its end 383 against the disc 384 to be picked up by the shoulder 385 at the proper time for operating the labeling device one cycle of operation when the package that was at station (5) reaches station (6).

Referring to Figure 21 the labeler operating 20 clutch of Figures 25 and 27 will result in reciprocation of the rod 232 to cause the pawl 229 to rotate the ratchet wheel 228 one-fourth revolution for thereby advancing the strip of labels 218 the distance of one label.

The shearing knife 257 operates every cycle 25 of the machine and so does the label carrying head 280 and its associated parts. The head can carry a label however only when one is fed down by the feed rollers 224 and 248 and since they are driven by the clutch mechanism operated by the trip rod 377 I thus insure that none of the labels are wasted but are brought into position to be cut off by the knives 256 and 257 and carried by the head 280 only when there is a package to receive the label.

35 After the label comes down in front of the head it is held there by the rod 300 before the vacuum acts in the pasageway 306 and while the knives are cutting the label off. Soon after the head 280 begins to advance toward the package 40 the valve vent 314 of Figure 23 is closed so that vacuum is produced in the pasageway 306 of the head 280 to thereafter hold the label in position while the rod 300 is moved out of the way.

The label is held by the vacuum until it is deposited against the end of the package P in Figures 18 and 20, and the spring 282 permits the head 280 to seek a level seating against the left end of the package in opposition to the floating head 333 and the spring 339. The two springs 50 opposing each other provide a slight compression that insures a tight engagement of the label with the package and since the label has a heat-seal surface and the head 280 is heated by the heater 281 such surface is softened and sealed 55 against the package shown by dot and dash lines in Figure 21.

While I have shown only one labeling device, it is obvious that a second one in place of the head 333 may be provided where it is desirable to place a label on each end of the package P. The details of such labeler would be substantially the same as those of the labeler shown.

From the foregoing specification, it will be obvious that all the folding operations on the wrapper are performed and the package is completely heat sealed by the time it reaches station (5) or in one-half revolution of the head R. By performing folding operations between stations (1) and (2) and at station (3) combined with effecting the first end flap folds by the ram elevating the article into the head and the fourth end flap fold being a result of movement of the head, and by the proper application of heat for sealing both the circumferential and the end flaps, 70 I am able to accomplish the complete packag-

ing of the article in a half revolution of the head and utilize a checking means at the end of the half revolution or at station (5) for the purpose of operating the label feeding mechanism for any package at station (5), the labeling thereof occurring then at station (6). This permits discharge of the wrapped and labeled package at station (7) so that the package can be discharged along the fore and aft axis of the machine. Thus the direction of discharge is natural for ease of arrangement of the discharge and take-away conveyors.

At station (7) as shown in Figure 30 the arm 19 is actuated so that the shoe 78 thereon discharges the package P by moving it from the dotted position to the full line position, this being accomplished by the arm 367 rocking to the position shown in this figure (dotted position of Figure 8). The continuously travelling belts 400 and 401 engage the ends of the package at this point and slide it along the platform 399 until the package leaves the discharge end of the platform and is deposited on the take-away conveyor belt 416. This belt may extend to a discharge table or to mechanism for placing wrapped packages in cartons or the like.

By providing a rotary head with a relatively large number of pockets to receive articles the wrapping machine may operate at relatively great speed to produce a large number of completed packages per hour without excessively fast travel of the package as it moves from station to station. The design of the parts is compact so that all operations are performed in a minimum of space and I have found that the resulting machine has great production possibilities.

While my machine has been illustrated as adapted for the wrapping of round sandwiches it works equally as well with square ones, the pockets of the head receiving the square sandwiches with equal facility and performing the wrapping and labeling operations on them without the necessity of making any changes to adapt the machine for square instead of round sandwiches.

As shown in Figures 32 and 33 the length of the package can be varied and this is made possible by the various adjustments for widening the rotor pockets, spacing the end flap folder plates farther apart and changing the distance between the take-away belts 400 and 401 by means of the various set screw and clamp screw arrangements described.

Some changes may be made in the construction and arrangement of the parts of my machine without departing from the real spirit and purpose of my invention, and it is my intention to cover by my claims any modified forms of structure or use of mechanical equivalents which may be reasonably included within their scope.

I claim as my invention:

1. In a wrapping machine a rotor having a plurality of axially elongated article receiving pockets therearound having open ends and an open outer side, each of said pockets having a movable article gripping member, means for imparting intermittent rotation to said rotor to move the pockets thereof to successive stations each cycle of operation of the wrapping machine, an article carrying conveyor adapted to receive articles to be wrapped and to convey them to one of said stations, a ram at said station for moving the articles from the successive pockets of said conveyor and a wrapper therefor into the open

sides of said pockets of said rotor, means to move the article gripping member of a rotor pocket receiving an article and wrapper to a position for reception of the article and wrapper, each pocket of said rotor having radially movable first end flap folder blades at the open ends of the pocket which are retained against movement as the article is moved by said ram into a pocket of the rotor, an arcuate first circumferential flap folder swingable on the shaft of said rotor across the open outer side of the pocket, stationary arcuate flap folder fingers adjacent the periphery of said rotor and extending from adjacent the station thereof that receives the article to adjacent the next station thereof, a heater shoe located at a station of said rotor beyond the ends of said fingers, a rock arm carrying said heater shoe, means for swinging said rock arm for moving said heater shoe toward the rotor while it is stationary, reciprocably mounted second end flap folder blades at the open ends of said pockets and positioned at another station of said rotor, means for moving said last blades inwardly of said rotor, projections engageable with said first end flap folder blades to move them out of the way of said second end flap folder blades, said projections being movable simultaneously with said second end flap folder blades, third end flap folder blades at the open ends of said pockets, means for mounting said last blades for rotary wiping movement over said second end flap folder blades, stationary arcuate shoes constituting fourth and flap folders at the open ends of said pockets as said rotor is further rotated, said shoes being spaced farther apart at their ends where the article and wrapper enter between them than at their other ends, said other ends being resiliently biased toward each other, said shoes including heaters for the ends of a wrapped package as the rotor is advanced and during the time it is stationary with a package intermediate the ends of said arcuate shoes, a second rock arm, a heater carried thereby and engageable with said circumferential flaps while the package is at said last station, means for rocking said second rock arm simultaneously with the rocking of said first rock arm, means for checking whether or not there is a package at a station beyond said arcuate shoes, said last means comprising a pivoted arm to which movement is imparted each cycle of operation of the wrapping machine, said arm having a part to extend into a pocket of said rotor, labelling mechanism comprising a movable head for carrying a label to a position against the end of a package at the station beyond said checking means, means for producing a vacuum in said head, the face of said head being perforated in communication with said means to hold a label thereon, means for feeding a strip of labels to said head and cutting a label off said strip for each package, a clutch mechanism being operated by said checking means to in turn cause operation of said label feeding and cutting mechanism each time said checking means determines that there is a package at said station beyond said arcuate shoes, valve means for relieving the vacuum in said head when a label is being fed by said label feeding means to a position in front of said head, means to mechanically engage the label with said head until said valve is closed and the vacuum is established for holding said label to said head, said last means being moved out of the way after the vacuum is established and before said head is moved toward the package, said head being floatingly mounted by means of a

spring connection for finding of itself a square seating against the end of the package, spring means at the opposite end of the package opposing said head, and means for discharging the wrapped and labelled package from said rotor.

2. In a wrapping machine of the character disclosed, a rotor, said rotor having a plurality of axially elongated article receiving pockets therearound having open ends and an open outer side, each of said pockets having a movable article gripping member, means for imparting intermittent rotation to said rotor to move the pockets thereof to successive stations, an article carrying conveyor adapted to receive articles to be wrapped and to convey them to one of said stations, means at said station for moving the articles from the successive pockets of said conveyor and a wrapper therefor into the open sides of said pockets of said rotor, means to move the article gripping member of a rotor pocket receiving an article and wrapper to a position for reception of the article and wrapper, each pocket of said rotor having radially movable first end flap folder blades at the open ends of the pocket, means to positively move said blades to a position where they effect a first end flap fold on the wrapper, a first circumferential flap folder movable across the open side of the pocket, a second circumferential flap folder means adjacent the periphery of said rotor following said one of said stations, a heater shoe located at a station beyond the outlet end of said last means, means for moving said heater shoe toward the rotor while it is stationary, second end flap folder blades at the open ends of said pockets positioned at another station of said rotor, means for moving said last blades toward said rotor projections engageable with said first end flap folder blades to move them out of the way of said second end flap folder blades, said projections being movable simultaneously with said second end flap folder blades, third end flap folder blades at the open ends of said pockets, means for mounting said last blades for rotary wiping movement over said second end flap folder blades, arcuate shoes constituting fourth end flap folders at the open ends of said pockets as said rotor is further rotated, heaters for the ends of a wrapped package as the rotor is advanced and during the time it is stationary with a package intermediate the ends of said arcuate shoes, means for checking whether or not there is a package at a station beyond said arcuate shoes, labelling mechanism comprising a movable head for carrying a label to a position against the end of a package at the station beyond said checking means, means for producing a vacuum in said head, the face of said head being perforated in communication with said means to hold a label thereon, means for feeding a strip of labels to said head and cutting a label off said strip for each package, clutch mechanism for operating said last means each time it engages a package at said station beyond said arcuate shoes, said clutch mechanism being operated by said checking means, valve means for relieving the vacuum in said head when a label is being fed by said label feeding means to a position in front of said head, said head being floatingly mounted by means of a spring connection for finding of itself a square seating against the end of the package, spring means at the opposite end of the package opposing said head, and means for discharging the wrapped and labelled package from said rotor.

3. In a wrapping machine of the character dis-

closed, a rotor, said rotor having a plurality of axially elongated article receiving pockets therearound having open ends and an open outer side, each of said pockets having a movable article gripping member, means for imparting intermittent rotation to said rotor to move the pockets thereof to successive stations, an article carrying conveyor adapted to receive articles to be wrapped and to convey them to one of said stations, means at said station for moving the articles from the successive pockets of said conveyor and a wrapper therefor into the open sides of said pockets of said rotor, means to move the article gripping member of a rotor pocket receiving an article and wrapper to a position for reception of the article and wrapper, each pocket of said rotor having radially movable first end flap folder blades at the open ends of the pocket, means to positively move said blades to a position where they effect a first end flap fold on the wrapper, a first circumferential flap folder movable across the open side of the pocket, a second circumferential flap folder means adjacent the periphery of said rotor following said one of said stations, a heater shoe located at a station beyond the outlet end of said last means, means for moving said heater shoe toward the rotor while it is stationary, second end flap folder blades at the open ends of said pockets positioned at another station of said rotor, means for moving said last blades toward the rotor projections engageable with said first end flap folder blades to move them out of the way of said second end flap folder blades, said projections being movable simultaneously with said second end flap folder blades, third end flap folder blades at the open ends of said pockets, means for mounting said last blades for wiping movement over said second end flap folder blades, arcuate shoes constituting four end flap folders at the open ends of said pockets as said rotor is further rotated, heaters for the ends of a wrapped package as the rotor is advanced and during the time it is stationary with a package intermediate the ends of said arcuate shoes, means for checking whether or not there is a package at a station beyond said arcuate shoes, labelling mechanism comprising a movable head for carrying a label to a position against the end of a package at the station beyond said checking means, means for producing a vacuum in said head, the face of said head being perforated in communication with said means to hold a label thereon, means for feeding a strip of labels to said head and cutting a label off said strip for each package, clutch mechanism for operating said last means, said clutch mechanism being operated by said checking means each time it engages a package at said station beyond said arcuate shoes, spring means at the opposite end of the package opposing said head, and means for discharging the wrapped and labelled package from said rotor.

4. In a machine of the character disclosed, a rotor having axially elongated article receiving pockets therearound having open ends and an open outer side, means for imparting intermittent rotation to said rotor to move the pockets thereof to successive stations, means for moving articles to be wrapped and a wrapper therefor one at a time into the open sides of successive pockets of said rotor at a first station, each pocket having radially movable first end flap folder blades at the open ends of the pocket, means for closing the open side of the pocket, a heater shoe located at a further station of said rotor, second end flap folder blades at the open

75

ends of said pockets, means at a still further station of said rotor for moving said last blades inwardly of said rotor while a pocket thereof is at said still further station, third end flap folder blades at the open ends of said pockets, means for mounting said last blades for rotary wiping movement over said second end flap folder blades, said means for mounting including a slot and pin connection and a rotatable crank for each blade, stationary arcuate shoes constituting fourth end flap folders at the open ends of said pockets as said rotor is further rotated, said shoes being spaced farther apart at their ends where the article and wrapper enter between them than at their other ends, said other ends being resiliently biased toward each other, said shoes including heaters, means for checking whether or not there is a package at a station beyond said arcuate shoes, said last means comprising a pivoted arm to which movement is imparted each cycle of operation of the wrapping machine, said arm having a part to extend into a pocket of said rotor, labelling mechanism comprising a movable head for carrying a label to a position against the end of a package at the station beyond said checking means, means for producing a vacuum in said head, the face of said head being perforated in communication with said means to hold a label thereon, means for feeding a strip of labels to said head and cutting a label off said strip for each package, a clutch mechanism for operating said last means, said clutch mechanism being operated by said pivoted arm each time it engages a package at said station beyond said arcuate shoes, valve means for relieving the vacuum in said head when a label is being fed by said label feeding means to a position in front of said head, means to mechanically engage the label with said head until said valve is closed and the vacuum is established for holding said label to said head, said last means being moved out of the way after the vacuum is established, said head being floatingly mounted for finding of itself a square seating against the end of the package, spring means at the opposite end of the package opposing said head, and means for discharging the wrapped and labelled package from said rotor.

5. In a machine of the character disclosed, a rotor having axially elongated article receiving pockets therearound having open ends and an open outer side, means for imparting intermittent rotation to said rotor to move the pockets thereof to successive stations, means for moving articles to be wrapped and a wrapper therefor one at a time into the open sides of successive pockets of said rotor as they stop at a first one of said stations, each pocket having radially movable first end flap folder blades at the open ends of said pockets, means for closing the open side of the pocket, a heater shoe located at a station of said rotor for the ends of a wrapped package, second end flap folder blades at the open ends of said pockets, means at a further station of said rotor for moving said last blades inwardly of said rotor while a pocket thereof is stationary at said further station, third end flap folder blades at the open ends of said pockets, means for moving said last blades, stationary arcuate shoes constituting fourth end flap folders at the open ends of said pockets as said rotor is further rotated, said shoes including heaters for the ends of a wrapped package as the rotor is advanced, means for checking whether or not there is a package at a station beyond said arcuate shoes, said last

means comprising a pivoted arm to which movement is imparted each cycle of operation of the wrapping machine, said arm having a part to extend into a pocket of said rotor, labelling mechanism comprising a movable head for carrying a label to a position against the end of a package at the station beyond said checking means, means for producing a vacuum in said head, the face of said head being perforated in communication with said means to hold a label thereon, means for feeding a strip of labels to said head and cutting a label off said strip for each package, a clutch mechanism for operating said last means, said clutch mechanism being operated by said pivoted arm each time it engages a package at said station beyond said arcuate shoes, said head being floatingly mounted for finding of itself a square seating against the end of the package, spring means at the opposite end of the package opposite said head, and means for discharging the wrapped and labelled package from said rotor.

6. In a wrapping machine of the character disclosed, a rotor having pockets, means for imparting intermittent rotation to said rotor to move the pockets thereof to successive stations, means to wrap a wrapper around an article in each pocket as said rotor is advanced station to station and for heat sealing the wrapper in relation to the article, means for checking whether or not there is a package at a station beyond said wrapping and heat sealing means, said checking means comprising a pivoted arm to which movement is imparted each cycle of operation of the wrapping machine, said arm having a part to extend into a pocket of said rotor, at said last mentioned station, labelling mechanism comprising a movable head for carrying a label to a position against the end of a package at the station beyond said checking means, means for producing a vacuum in said head, the face of said head being perforated in communication with said last means to hold a label thereon, means for feeding a strip of labels to said head and cutting a label off said strip for each package, a clutch mechanism for operating said last means, said clutch mechanism being operated by said checking means to in turn cause operation of said label feeding and cutting mechanism each time said pivoted arm engages a package at said checking station, valve means for relieving the vacuum in said head when a label is being fed by said label feeding means to a position in front of said head, means to mechanically engage the label with said head until said valve is closed and the vacuum established for holding said label to said head, said last means being moved out of the way after the vacuum is established and before said head is moved toward the package, said head being floatingly mounted by means of a spring connection for finding of itself a square seating against the end of the package, spring means at the opposite end of the package opposing said head, and means for discharging the wrapped and labelled package from said rotor.

7. In a wrapping machine, a rotor having pockets, means for imparting intermittent rotation to said rotor, to move the pockets thereof to successive stations, means to wrap a wrapper around an article in each pocket as said rotor is advanced station to station and for heat sealing the wrapper in relation to the article, means for checking whether or not there is a package at a station beyond said last means, said check-

ing means comprising a pivoted element to which movement is imparted each cycle of operation of the wrapping machine, said element having a part to extend into a pocket of said rotor, labelling mechanism comprising a movable head for carrying a label to a position against the end of a package at a station beyond said checking means, means for producing a vacuum in said head to hold a label thereagainst, means for feeding a strip of labels to said head and cutting a label off said strip for each package, clutch mechanism for operating said last means, said clutch mechanism being operated by said checking means to cause said label feeding and cutting mechanism to operate only when there is a package at said checking station, said head being floatingly mounted by means of a spring connection for finding of itself a square seating against the end of a package, means at the opposite end of the package to support it in opposition to said head and its spring connection, and means for discharging the wrapped and labelled package from said rotor.

8. A wrapping machine comprising a pocketed rotor, means for imparting intermittent rotation to said rotor to move the pockets thereof to successive stations, means to wrap a wrapper around an article in each pocket as said rotor is advanced, means for heat sealing the wrapper in relation to the article, means for checking whether or not there is a package at a station beyond said heat sealing means comprising a pivoted arm to which movement is imparted each cycle of operation of the wrapping machine, said arm having a part to extend at said last mentioned station into a pocket of said rotor, labelling mechanism comprising a movable head for carrying a label to a position against the end of a package at another station beyond said checking means, means for feeding a strip of labels to said head and cutting a label off said strip for each package, clutch mechanism for operating said last means, said clutch mechanism being operated by said pivoted arm to cause said label feeding and cutting mechanism to operate only when there is a package at said checking station, said head being floatingly mounted for finding of itself a square seating against the end of a package, means at the opposite end of the package to support it in opposition to said head, and means for discharging the wrapped and labelled package from said rotor.

9. In a wrapping machine of the character disclosed, a rotor, said rotor having a plurality of axially elongated article receiving pockets therearound having open ends and an open outer side, each of said pockets having a movable article gripping member, means for imparting intermittent rotation of said rotor to move the pockets thereof to successive stations each cycle of operation of the wrapping machine, an article carrying conveyor adapted to receive articles to be wrapped and to convey them to one of said stations, a ram at said station for moving the articles from said conveyor and a wrapper for each article into the open sides of said pockets of said rotor, means to move the article gripping member of a rotor pocket receiving an article and wrapper to a position to receive them, means movable radially of said rotor and constituting first end flap folders at the open ends of said pockets as the article and wrapper are caused by said ram to enter a pocket of said rotor, a heater shoe located at a station of said rotor beyond said last means, means for moving said heater

shoe toward said rotor while it is stationary, means constituting second and third end flap folders at the open ends of said pockets at one station of rotation of said rotor and constituting fourth end flap folders at the open ends of said pockets as the rotor advances thereafter, said last means including heaters for the ends of a wrapped package as the rotor is advanced and during the time it is stationary with a package intermediate the ends of said last means, means for checking whether or not there is a package at a station beyond said last means, said checking means comprising a pivoted arm to which movement is imparted each cycle of operation of the wrapping machine, said arm having a part to extend into a pocket of said rotor, labelling mechanism comprising a movable head for carrying a label to a position against the end of a package at the station beyond said checking means, means for producing a vacuum in said head, the face of said head being perforated in communication with said means to hold a label thereon, means for feeding a strip of labels to said head and cutting a label off said strip for each package, a clutch mechanism for operating said last means, said clutch mechanism being operated by said checking means to in turn cause operation of said label feeding and cutting mechanism each time said pivoted arm engages a package at said last station, valve means for relieving the vacuum in said head when a label is being fed by said label feeding means to a position in front of said head, means to mechanically engage the label with said head until said valve is closed and the vacuum thereby established for holding said label to said head, said last means being moved out of the way after the vacuum is established and before said head is moved toward the package, said head being floatingly mounted by means of a spring connection for finding of itself a square seating against the end of the package, spring means at the opposite end of the package opposing said head, and means for discharging the wrapped and labelled package from said rotor.

10. In a wrapping machine, a rotor having a plurality of axially elongated article receiving pockets having open ends and an open outer side, means for imparting intermittent rotation of said rotor to move the pockets thereof to successive stations, a pocket conveyor adapted to receive articles to be wrapped and to convey them to one of said stations, means at said station for moving the articles from said conveyor and a wrapper for each article into the open sides of said pockets of said rotor, means movable radially of said rotor and constituting first end flap folders at the open ends of said pockets as the article and wrapper enter a pocket of said rotor, means constituting second and third end flap folders at the open ends of said pockets at one station of rotation of said rotor, stationary means constituting fourth end flap folders at the open ends of said pockets as the rotor advances thereafter, means for checking whether or not there is a package at a station beyond said last means, labelling mechanism comprising a movable head for carrying a label to a position against the end of a package at the station beyond said checking means, means for producing a vacuum in said head, the face of said head being perforated in communication with said means to hold a label thereon, means for feeding a strip of labels to said head and cutting a label off said strip for each package, a clutch mechanism for operating

said last means, said clutch mechanism being operated by said checking means to in turn cause operation of said label feeding and cutting mechanism each time said checking means determines that there is a package at said previous station, said head being floatingly mounted by means of a spring connection for finding of itself a square seating against the end of the package, spring means at the opposite end of the package opposing said head, and means for discharging the wrapped and labelled package from said rotor.

11. In a machine of the character disclosed, a rotor, said rotor having a plurality of axially elongated article receiving pockets having open ends and an open outer side, each of which has a movable article gripping member, means for imparting intermittent rotation to said rotor to move the pockets thereof to successive stations, an article carrying conveyor adapted to receive articles to be wrapped and to convey them to one of said stations, a ram at said station for moving the articles from said conveyor and wrappers therefor into the open sides of said pockets of said rotor, means to move the article gripping member of a rotor pocket receiving an article and wrapper to a position permitting such reception, each pocket of said rotor having first end flap folder blades at the open ends of the pocket, an arcuate first circumferential flap folder swingable on the axis of said rotor and around its circumference in the direction of its rotation to fold the first circumferential flap around the article, reciprocably mounted second end flap folder blades at the open ends of said pockets, means at one station of said machine for moving said last blades inwardly of said rotor while a pocket thereof is stationary at said station, third end flap folder blades at the open ends of said pockets, means for mounting said last blades for wiping movement over said second end flap folder blades, arcuate shoes constituting fourth end flap folders at the open ends of said pockets as said rotor is further rotated, said shoes being spaced farther apart at their ends where the article and wrapper enter between them than at their other ends, said other ends being resiliently biased toward each other, and means for discharging the wrapped package from said rotor.

12. In a wrapping machine of the character disclosed, a rotor, said rotor having a plurality of axially elongated article receiving pockets therearound having open ends and an open outer side, each of said pockets having a movable article gripping member, means for imparting intermittent rotation to said rotor to move the pockets thereof to successive stations each cycle of operation of the wrapping machine, an article carrying conveyor having pockets adapted to receive articles to be wrapped and to convey them to one of said stations, a ram at said station for moving the articles from the successive pockets of said conveyor and a wrapper for each article into the open sides of said pockets of said rotor, means to move the article gripping member of a rotor pocket when it receives an article and wrapper to a position affording such reception, each pocket of said rotor having radially movable first end flap folder blades at the open ends of the pocket which are retained against movement as the article is moved by said ram into a pocket of the rotor, each of said rotor pockets carrying a spring shoe engaged by the article and its wrapper as they are moved into the rotor pocket by said ram,

said shoes holding the wrappers against the articles, an arcuate first circumferential flap folder swingable on the shaft of said rotor across the open outer side of the pocket, stationary arcuate flap folder fingers adjacent the periphery of said rotor and extending from adjacent the station thereof that receives the article to adjacent the next station thereof, a heater shoe located at a station of said rotor beyond the ends of said fingers, a rock arm carrying said heater shoe, means for swinging said rock arm for moving said heater shoe toward said rotor while it is stationary, reciprocably mounted second end flap folder blades at the open ends of said pockets positioned at another station of said rotor, means for moving said last blades inwardly of said rotor while a pocket thereof is stationary at said another station, projections engageable with said first end flap folder blades to move them out of the way of said second end flap folder blades, said projections being movable simultaneously with said second end flap folder blades, third end flap folder blades at the open ends of said pockets, means for mounting said last blades for wiping movement over said second end flap folder blades, said means for mounting including rotatable cranks, stationary arcuate shoes constituting fourth end flap folders as said rotor is further rotated, said shoes being spaced farther apart at their ends where the article and wrapper enter between them than at their other ends, said other ends being resiliently biased toward each other, said shoes including heaters for the ends of a wrapped package as the rotor is advanced and during the time it is holding a package stationary intermediate the ends of said arcuate shoes, and means for discharging the wrapped package from said rotor.

13. In a wrapping machine, a rotor having a plurality of axially elongated article receiving pockets having open ends and an open outer side, each of said pockets having a movable article gripping member, means for imparting intermittent rotation to said rotor to move the pockets thereof to successive stations, an article carrying conveyor, a ram at one of said stations for moving articles from said conveyor and wrappers therefor into the open sides of said pockets of said rotor, means to move the article gripping member of a rotor pocket as it receives an article and wrapper to a position affording such reception, each pocket of said rotor having first end flap folder blades at the open ends of the pocket, each of said rotor pockets carrying a normally extended spring shoe engaged by the article and its wrapper and thereby retracted against the spring bias as they are moved into the rotor pocket by said ram, a first circumferential flap folder swingable on the axis of said rotor and thereby movable circumferentially around said rotor, stationary flap folding means adjacent the periphery of said rotor and extending from adjacent the station thereof that receives the article to adjacent the next station thereof, a heater, means for moving said heater toward said rotor each cycle of operation of the machine, second end flap folder blades at the open ends of said pockets positioned at another station of said rotor while a pocket thereof is stationary at said another station, means for moving said last blades inwardly of said rotor, third end flap folder blades at the open ends of said pockets, means for moving said last blades for wiping movement over said second end flap

folder blades, arcuate shoes constituting fourth end flap folders at the open ends of said pockets as said rotor is further rotated, heaters for heating the ends of a package after they are folded down by said end flap folders, and means for discharging the completed package from said rotor.

14. In a wrapping machine of the character disclosed, a rotor, said rotor having a plurality of axially elongated article receiving pockets therearound having open ends and an open outer side, each of said pockets having a movable article gripping member, means for imparting intermittent rotation to said rotor to move the pockets thereof to successive stations each cycle of operation of the wrapping machine, an article carrying conveyor adapted to receive articles to be wrapped and to convey them to one of said stations, a ram at said station for moving the articles from said conveyor and wrappers therefore into the open sides of said pockets of said rotor, means to move the article gripping member of a rotor pocket receiving an article and wrapper to a position for such reception, each pocket of said rotor having radially movable first end flap folder blades at the open ends of the pocket which are retained against movement as the article is moved by said ram into a pocket of the rotor for effecting a first end flap fold on the wrapper, each of said rotor pockets carrying a spring shoe engaged by the article and its wrapper as they are moved into the rotor pocket by said ram, an arcuate first circumferential flap folder swingable on the shaft of said rotor across the open side of the pocket, stationary arcuate flap folder fingers adjacent the periphery of said rotor and extending from adjacent the station thereof that receives the article to adjacent the next station thereof, reciprocably mounted second end flap folder blades at the open ends of said pockets positioned at another station of said rotor, means for moving said last blades inwardly of said rotor while a pocket thereof is stationary at said another station, projections engageable with said first end flap folder blades to move them out of the way of said second end flap folder blades, said projections being movable simultaneously with said second end flap folder blades, third end flap folder blades at the open ends of said pockets, means for mounting said last blades for rotary wiping movement over said second end flap folder blades, said means for mounting comprising a bell crank carrying each blade on the outer end of one arm of the bell crank, the outer end of the other arm having a slot and pin connection with a stationary portion of the wrapping machine, rotatable cranks having their crank pins rotatably mounted in the bends of said bell cranks, stationary arcuate shoes constituting fourth end flap folders at the open ends of said pockets as said rotor is further rotated, said shoes being spaced farther apart at their ends where the article and wrapper enter between them than at their other ends, said other ends being resiliently biased toward each other, each pocket of said rotor finally reaching a discharge station, and means for positively moving the spring shoe at said discharge station to cause it to effect discharge of the wrapped package from said rotor.

15. In a wrapping machine, a rotor having axially elongated article receiving pockets having open ends and an open outer side, means for imparting intermittent rotation to said rotor to move the pockets thereof to successive stations each cycle of operation of the wrapping machine, an article carrying conveyor

move the pockets thereof to successive stations, a pocket conveyor adapted to receive articles to be wrapped and to convey them to one of said stations, a ram at said station for moving the articles from the successive pockets of said conveyor and a wrapper for each article into the open sides of said pockets of said rotor, each pocket of said rotor having radially movable first end flap folder blades at the open ends of the pocket, each of said rotor pockets carrying a spring shoe engaged by the article and its wrapper as they are moved into the rotor pocket by said ram, an arcuate first circumferential flap folder movable across the open side of the pocket, reciprocably mounted second end flap folder blades at the open ends of said pockets positioned at another station of said rotor, means for moving said last blades inwardly of said rotor while a pocket thereof is stationary at said another station, third end flap folder blades at the open ends of said pockets, means for mounting said last blades for wiping movement over said second end flap folder blades, stationary arcuate shoes constituting fourth end flap folders at the open ends of said pockets as said rotor is further rotated, and means for discharging the wrapped package from said rotor comprising an element moved by the wrapping machine each cycle of operation thereof for positively moving the spring shoes of the successive pockets to effect discharge of the wrapped package from the rotor pocket at a station beyond said stationary arcuate shoes.

16. In a wrapping machine of the character disclosed, a rotor, said rotor having a plurality of axially elongated article receiving pockets therearound having open ends and an open outer side, each of said pockets having a movable article gripping member, means for imparting intermittent rotation to said rotor to move the pockets thereof to successive stations each cycle of operation of the wrapping machine, a pocket conveyor adapted to receive articles to be wrapped and to convey them to one of said stations, a ram at said station for moving the articles from the successive pockets of said conveyor and wrappers therefor into the open sides of said pockets of said rotor, means to move the article gripping member of a rotor pocket receiving an article and wrapper to a position for such reception, each pocket of said rotor having movable first end flap folder blades at the open ends of the pocket which are retained against movement as the article is moved by said ram into a pocket of the rotor, each of said rotor pockets carrying a spring shoe engaged by the article and its wrapper as they are moved into the rotor pocket by said ram, means constituting second and third end flap folders at the open ends of said pockets at one station of rotation of said rotor and further means constituting fourth end flap folders at the open ends of said pockets as the rotor advances thereafter, and means for positively moving said spring shoes as they reach a discharge station to cause each one to effect discharge of the wrapped package from its respective rotor pocket at a discharge station of said rotor.

17. In a machine of the character disclosed, a rotor, said rotor having a plurality of axially elongated article receiving pockets therearound having open ends and an open outer side, each of said pockets having a movable article gripping member means for imparting intermittent rotation to said rotor to move the pockets thereof to successive stations each cycle of operation of the wrapping machine, an article carrying conveyor

adapted to receive articles to be wrapped and to convey them to one of said stations, a ram at said station for moving the articles from the successive pockets of said conveyor and a wrapper therefor into the open sides of said pockets of said rotor, means to move the article gripping member of that rotor pocket receiving an article and wrapper to a position to afford such reception, each pocket of said rotor having radially movable first end flap folder blades at the open ends of the pocket which are retained against movement as the article is moved by said ram into a pocket of the rotor, an arcuate first circumferential flap folder swingable on the shaft of said rotor across the open outer side of the pocket, stationary arcuate flaps folder fingers adjacent the periphery of said rotor and extending from adjacent the station thereof that receives the article to adjacent the next station thereof, a heater shoe located at a station of said rotor beyond the outlet ends of said fingers, a rock arm carrying said heater shoe, means for swinging said rock arm for moving said heater shoe toward the rotor while it is stationary, reciprocably mounted second end flap folder blades at the open ends of said pockets positioned at another station of said rotor, means for moving said last blades inwardly of said rotor while a pocket thereof is stationary at said another station, projections engageable with said first end flap folder blades to move them out of the way of said second end flap folder blades, said projections being movable simultaneously with said second end flap folder blades, third end flap folder blades at the open ends of said pockets, means for mounting said last blades for rotary wiping movement over said second end flap folder blades, said means for mounting comprising a bell crank carrying each blade on the outer end of one arm of the bell crank, the outer end of the other arm having a slot and pin connection with a stationary portion of the wrapping machine, rotatable cranks having their crank pins rotatably mounted in the bends of said bell cranks, stationary arcuate shoes constituting fourth end flap folders at the open ends of said pockets as said rotor is further rotated, said shoes being spaced farther apart at their ends where the article and wrapper enter between them than at their other ends, said other ends being resiliently biased toward each other, said shoes including heaters for heating said fourth end flap folds as the rotor is advanced and during the time it is stationary with a package intermediate the ends of said arcuate shoes, and means for discharging the wrapped package from said rotor.

18. In a wrapping machine of the character disclosed, a rotor, said rotor having a plurality of axially elongated article receiving pockets therearound having open ends and an open outer side, each of said pockets having a movable article gripping member, means for imparting intermittent rotation to said rotor to move the pockets thereof to successive stations each cycle of operation of the wrapping machine, a pocketed article carrying conveyor adapted to receive articles to be wrapped and to convey them to one of said stations, means at said station for moving the articles from the successive pockets of said conveyor and a wrapper for each article into the open sides of said pockets of said rotor, means to move the article gripping member of a rotor pocket as it receives an article and wrapper, to a position to afford such reception, means constituting first end flap folders at the open ends of said pockets as an article and wrapper

are caused by said first means to enter a pocket of said rotor, an arcuate first circumferential flap folder swingable on the shaft of said rotor across the open side of the pocket, stationary arcuate flaps folder fingers adjacent the periphery of said rotor and extending from adjacent the station thereof that receives the article to adjacent the next station thereof, a heater shoe located at said next station of said rotor, a rock arm carrying said heater shoe, means for swinging said rock arm for moving said heater shoe toward the rotor while it is stationary, reciprocably mounted second end flap folder blades at the open ends of said pockets positioned at another station of said rotor, means for moving said last blades inwardly of said rotor while a pocket thereof is stationary at said another station, projections engageable with said first end flap folder blades to move them out of the way of said second end flap folder blades, said projections being movable simultaneously with said second end flap folder blades, third end flap folder blades at the open ends of said pockets, means for mounting said last blades for rotary wiping movement over said second end flap folder blades, said means for mounting comprising bell cranks carrying said blades, said bell cranks having slot and pin connections with a stationary portion of the wrapping machine and rotatable cranks having their crank pins rotatably mounted in said bell cranks, stationary arcuate shoes constituting fourth end flap folders as said rotor is further rotated, said shoes being spaced farther apart at their ends where the article and wrapper enter between them than at their other ends, said other ends being resiliently biased toward each other, said shoes including heaters for the ends of a wrapped package as the rotor is advanced and during the time it is stationary with a package intermediate the ends of said arcuate shoes, and means for discharging the wrapped package from said rotor.

19. In a wrapping machine of the character disclosed, a rotor, said rotor having a plurality of axially elongated article receiving pockets therearound having open ends and an open outer side, each of said pockets having a movable article gripping member, means for imparting intermittent rotation to said rotor to move the pockets thereof to successive stations each cycle of operation of the wrapping machine, an article carrying conveyor adapted to receive articles to be wrapped and to convey them to one of said stations, a ram at said station for moving the articles from the successive pockets of said conveyor and a wrapper for each article into the open sides of said pockets of said rotor, means to move the article gripping member of a rotor pocket that receives an article and wrapper to a position for affording such reception, means constituting first end flap folders at the open ends of said pockets as said ram enters a pocket of said rotor, a first circumferential flap folder, means for moving the same across the open outer side of the pocket, arcuate flap folder means adjacent the periphery of said rotor and extending from adjacent the station thereof that receives the article to adjacent the next station thereof, reciprocably mounted second end flap folder blades at the open ends of said pockets positioned at another station of said rotor, means for moving said blades inwardly of said rotor while a pocket thereof is stationary at said another station, projections engageable with said first end flap folder means to move them out of the way of said second end flap folder blades, third end flap folder blades

at the open ends of said pockets, said projections being movable simultaneously with said second end flap folder blades, means for mounting said last blades for rotary wiping movement over said second end flap folder blades, stationary arcuate shoes constituting fourth end flap folders at the open ends of said pockets as said rotor is further rotated, said shoes being spaced farther apart at their ends where the article and wrapper enter between them than at their other ends, said other ends being resiliently biased toward each other, and means for discharging the wrapped package from said rotor.

20. A machine of the character disclosed comprising a rotor, said rotor having a plurality of axially elongated article receiving pockets therearound having open ends and an open outer side, each of said pockets having a movable article gripping member, means for imparting intermittent rotation to said rotor to move the pockets thereof to successive stations each cycle of operation of the wrapping machine, an article carrying conveyor adapted to receive articles to be wrapped and to convey them to one of said stations, a ram at said station for moving the articles from the successive pockets of said conveyor and a wrapper therefor into the open sides of said pockets of said rotor, means to move the article gripping member of a rotor pocket receiving an article and wrapper to a position affording such reception, each pocket of said rotor having radially movable first end flap folder blades at the open ends of the pocket which are retained against movement as the article is moved by said ram into a pocket of the rotor, a heater movable toward the rotor while it is stationary, reciprocably mounted second end flap folder blades at the open ends of said pockets positioned at another station of said rotor, means for moving said last blades inwardly of said rotor while a pocket thereof is stationary at said another station, projections engageable with said first end flap folder blades to move them out of the way of said second end flap folder blades, third end flap folder blades, said projections being movable simultaneously with said second end flap folder blades, means for mounting said last blades for rotary wiping movement over said second end flap folder blades, said means for mounting comprising a bell crank carrying each blade on the outer end of one arm of the bell crank, the outer end of the other arm having a slot and pin connection with a stationary portion of the wrapping machine, rotatable cranks having their crank pins rotatably mounted in the bends of said bell cranks, stationary arcuate shoes for performing fourth end flap folds on said wrapper as said rotor is further rotated, said shoes being spaced farther apart at their ends where the article and wrapper enter between them than at their other ends, said other ends being resiliently biased toward each other, said shoes including heaters for heating said fourth end flap folds as the rotor is advanced and during the time it is stationary with a package intermediate the ends of said arcuate shoes, and means for discharging the wrapped package from said rotor.

21. In a wrapping machine, a rotor having a plurality of axially elongated article receiving pockets therearound having open ends and an open outer side, means for imparting intermittent rotation to said rotor to move the pockets thereof to successive stations, an article carrying conveyor adapted to receive articles to be wrapped and to convey them to one of said stations, means

at said station for moving the articles from the successive pockets of said conveyor and a wrapper therefor into the open sides of said pockets of said rotor, each pocket of said rotor having radially movable first end flap folder blades at the open ends of the pocket which are retained against movement as the article is moved by said ram into a pocket of the rotor, a heater shoe located at a further station of said rotor, a rock arm carrying said heater shoe, means for swinging said rock arm for moving said heater shoe toward the rotor while it is stationary, reciprocably mounted second end flap folder blades at the open ends of said pockets, means at a still further station of said rotor for moving said last blades inwardly thereof while a pocket of said rotor is stationary at said still further station, said last blades having means movable simultaneously therewith for moving said first end flap folder blades out of the way as said second end flap folder blades so move, third end flap folder blades at the open ends of said pockets for rotary wiping movement over said second end flap folder blades, stationary arcuate shoes constituting fourth end flap folders at the open ends of said pockets as said rotor is further rotated, said shoes including heaters for the ends of a wrapped package, and means for discharging the wrapped package from said rotor.

22. In a wrapping machine, a rotor having a plurality of axially elongated article receiving pockets having open ends and an open outer side, means for imparting intermittent rotation to said rotor to move the pockets thereof to successive stations, an article carrying conveyor adapted to receive articles to be wrapped and convey them to one of said stations, means at said station for moving the articles from said conveyor and a wrapper therefor into the open sides of successive pockets of said rotor, each pocket of said rotor having radially movable first end flap folder blades at the open ends of the pocket which are retained against movement as the article is moved into a pocket of said rotor, a heater shoe located at a station of said rotor, means for moving said heater shoe toward the rotor while it is stationary, reciprocably mounted second end flap folder blades at the open ends of said pockets positioned at another station of said rotor, means for moving said last blades inwardly of said rotor while a pocket thereof is stationary at said another station and at the same time moving said first end flap folder blades radially inward in relation to said rotor, third end flap folder blades at the open ends of said pocket, means for moving said last blades over the ends of a wrapped package, stationary arcuate shoes constituting fourth end flap folders at the open ends of said pockets, and means for discharging the wrapped package from said rotor.

OSCAR SANDBERG.
